GIOVANNI EMANUELE ELIA, OF TURIN, ITALY.

EXPLOSIVE-MINE APPARATUS.

1,309,121.

Specification of Letters Patent. Patented July 8, 1919.

Application filed November 19, 1917. Serial No. 202,858.

To all whom it may concern:

Be it known that I, GIOVANNI EMANUELE ELIA, a subject of the King of Italy, residing at Turin, Italy, have invented certain new and useful Improvements in Explosive-Mine Apparatus, and I do hereby declare the following to be a full, clear, and exact description of the invention, such as will enable others skilled in the art to which it appertains to make and use the same.

This invention relates to explosive mines and is directed to the provision of apparatus for laying mines within an area which is so protected by the mines or the navy or the fortresses of the enemy as to make it too dangerous for surface vessels to enter it. The invention involves the provision of means for propelling a mine a predetermined distance which may be as much as a hundred or several hundred miles and then discharging it and an anchor for the mine. Preferably, the mine, the anchor, and the means connecting the mine to the anchor are such that when the mine and anchor are discharged, the mine automatically assumes a position at a predetermined distance below the surface of the sea.

In accordance with the invention, a self-propelled automatically steered boat is provided, either a surface boat or a submarine boat, arranged to carry a mine and its anchor, and the propelling apparatus of the boat is utilized to liberate the mine after the boat has proceeded a predetermined distance for which it was initially set to travel. Preferably the boat employed for conveying the mine is a surface boat, as the cost of construction of such a boat is small compared to that of a submarine boat for accomplishing the same purpose. It may be propelled by any suitable mechanism, such, for instance, as an electric motor supplied with current from a storage battery or an internal combustion engine, the former being preferably employed on account of its reliability. This boat may have an opening of substantial size in the bottom thereof normally closed against the entrance of water by a suitable closure, and after the boat has proceeded the distance for which it was set, the propelling mechanism or some other mechanism provided on the boat may be arranged to release or eject the closure from the opening so as to permit the sea water to enter the hull of the boat and cause the boat to sink. At the time

of the sinking of the boat, the mine is discharged or released so that it will assume the desired position in the water and be anchored in that position.

The type of mine which I prefer to employ is that consisting of a mine casing for the explosive, an anchor, a paying-out gear carried by the anchor, a cable extending from the paying-out gear to the mine casing, and a stop for the paying-out gear controlled by a suspended weight. The closure for the opening in the bottom of the boat may constitute the weight referred to. With such a construction the dropping of the weight from the opening in the bottom of the boat, effected automatically as above outlined, would cause the paying-out gear to be locked and to be held in the locked condition until the boat sank to the bottom, whereupon the pull of the weight would be released from the lock for the paying-out gear, allowing the latter to operate to permit the mine casing to ascend through the water until it reached the desired depth of submergence. At this point the operation of the paying-out gear would be arrested by any suitable mechanism so as to hold the mine at the desired position of submergence.

In combination with mechanism of the character described, I prefer to provide automatic means for exploding the mine in case the mechanism for sinking the boat or discharging the mine from the boat fails to operate after the mine has been conveyed the predetermined distance. The purpose of this mechanism is to eliminate the possibility of the enemy against whom the mine is sent, retrieving a mine apparatus which has failed to operate and turning it against those who devised it.

With such a mine-laying apparatus, it is possible to plant mines in a protected area without encountering any danger from the means employed for protecting that area. For instance, a substantial number of the self-propelled mine-carrying boats may be conveyed to a point adjacent to but outside the protected area of the enemy, each of them may be set to travel a selected distance and all of them may be started in operation and released for travel into the protected area. Preferably the boats would be sent forward under cover of darkness to reduce the possibility of interference with them by the enemy. Each boat would preferably be

provided with gyroscopically controlled steering mechanism for guiding it on the course selected for it. As each boat reached the end of its predetermined run, the automatic mechanism in the boat would operate to release or discharge the mine and the mechanism associated with the casing for the explosive of the mine would cause the casing to be anchored at the selected distance below the surface of the sea. In this way it would be possible to sow mines over an extended area which supposedly was protected against incursions of mine layers so as to cause the destruction of enemy ships which would proceed through the area feeling assured that it was free from danger.

The invention hereinabove outlined may be practised with apparatus varying between wide limits as to its character and structural features. The self-propelled boat for carrying the mine may be a surface boat or a submarine boat and may be constructed of any suitable materials; the boat may be propelled by any suitable form of motor mechanism; and the planting of the mine after the boat has proceeded the selected distance may be effected by causing the boat with the mine therein to sink or by discharging the mine from the boat. For this reason I desire to have it understood that the invention is not limited with respect to the structural characteristics of the apparatus employed for practising it, except as may be indicated by the terms employed in certain of the claims appended hereto.

I have illustrated diagrammatically in the accompanying drawings a mechanism which may be employed for practising the invention. In these drawings, Figure 1 is a diagrammatic view illustrating the mine-carrying boat in three different positions; Figs. 2 and 3 are diagrammatic longitudinal section and plan views respectively of the boat and the mine therein; Fig. 4 is a view illustrating certain of the parts of the mine; Fig. 5 is a diagrammatic view of certain of the electrical apparatus; and Fig. 6 is a sectional view of the weight for arresting the operation of the paying-out gear of the mine.

Referring first to Figs. 2 and 3, the self-propelled boat for conveying the mine is indicated at 7. It is preferably made of sheet steel pressed into the configuration required. It may be decked over entirely or to a considerable extent so as to prevent the entrance of water into the hull during the run. In the drawings, the boat is shown as decked over at 8, and a large opening is provided in this deck adapted to be closed by a removable cover 9. This cover is carried upon a hinge pin 10 carrying a crank 11, to which a rod 12 is pivotally connected and a coil spring 13 bears at one end upon a collar carried by rod 12 and at the other end upon

a stationary standard, the construction being such that when the rod 12 is released, it is moved in the direction of its length by the spring 13 to move the cover 9 from the closed position in which it is shown in Fig. 2 to an open position at right angles thereto.

The boat is provided with a propeller 14 driven from a suitable motor carried by the boat. In the present instance, an electric motor 15 is shown for this purpose, having its shaft 16 provided with a pinion meshing with a gear on a propeller shaft 17, which extends back through a suitable stuffing box and carries the propeller 14. Current is supplied to the motor 15 by a storage battery 80 contained within a battery box 18. The motor 15 may be belted to an air compressor 19 for supplying compressed air through a pipe 20 to a gyroscopic steering gear 21. This steering gear is connected by a link 22 to a crank on the rudder shaft. The specific construction of the gyroscopic steering gear need not be described in detail as it may be of any construction suitable for the purpose. The motor 15, compressor 19 and battery box 18, are preferably inclosed within a suitable compartment by a wall 23, so as to protect them against sea water, if such water were to gain entrance to the hull of the boat.

In the bottom of the hull of the boat is an opening of substantial size, and this is closed during the run of the boat by a closure 24. The closure may be held in the opening in any suitable manner, as for instance, by providing a recess in the closure adapted to receive the end of a reciprocating rod 25. At the end of the run of the boat the closure 24 is released from the opening in the hull of the boat automatically to permit water to enter the hull through the opening. For this purpose the propeller shaft 17 or any other shaft of the propelling mechanism is arranged to withdraw the end of rod 25 from the recess in the closure 24 after a predetermined period of operation of the propelling mechanism. This is indicated in Figs. 1 and 2 by connecting one end of rod 25 to a pivoted link 26 adapted to be engaged by a member 27 driven by the propelling mechanism of the boat. The driving mechanism for the member 27 includes a reduction gear and means for setting some part, such as the member 27, to cause operation of rod 25 at the predetermined time. The reduction gear is indicated in Fig. 2 by the worm 28 on the shaft 17 and the worm wheel 29 with which the worm meshes. The operating member of this mechanism consists of an arm 27 loose on the shaft of the worm wheel 29 and arranged to be set for operation at the desired point by a pin 30 for locking the arm 27 to any one of the teeth of a ratchet wheel 31 secured rigidly to the shaft of the worm wheel 29. The end of arm 27 is adapted to

engage the link 26 at the end of the run of the boat and move the rod 25 in the direction of its length to withdraw its end from the recess in the closure 24. For the purpose of insuring that the closure 24 will be ejected from the opening in the hull of the boat when it is released by a rod 25, a bell-crank lever 32 may be pivotally mounted adjacent to the closure 24 with one end connected to the rod 25 and the other end overlying the closure 24. When the rod 25 is moved to release closure 24, it operates the bell-crank lever 32 so that the free end of the lever comes down on top of the closure 24 as the end of rod 25 is disengaged from the closure and the lever 32 forces the closure 24 downwardly out of the opening in the hull of the boat. The parts of this mechanism, that is, parts 25, 26 and 32, are normally held in the positions in which they are shown in Fig. 2, by a spring 33 connected at one end to the rod 25 and at the other to a stationary element.

The mechanism for releasing the closure 24 for the opening in the hull of the boat may also be employed for effecting the opening of the cover 9 for the opening in the deck of the boat. In Fig. 2, the rod 12 is held in the position in which it is shown against the tension of spring 13 by a latch on the end of a rod 34. A spring normally presses this rod upwardly to hold its end in the notch in the end of rod 12. The lower end of rod 34 is connected to one end of a pivoted bell-crank lever 35 whose other end carries a pin 36 extending toward the link 26. When this link is operated by the arm 27, it is carried into engagement with the end of the pin 36, thereby rocking the lever 35 and pulling the rod 34 downwardly until the end of the rod releases the rod 12 and thus allows the spring 13 to turn the cover 9 to the upright open position.

Within the boat is the mine, consisting of the casing 37 for the explosive and the anchor 38. Within the anchor casing 38 is a paying-out gear illustrated diagrammatically in Fig. 4 as consisting of a reel 39 pivotally mounted upon the walls of the anchor casing 38. A cable 40 is wound on this reel and passes upwardly through a guide in the top of the anchor casing, its end being connected to an eye 41 on the mine casing 37. One end of the reel 39 is provided with gear teeth with which a locking device coacts. This locking device consists of a lever 42 pivotally mounted on a standard 43 on the mine casing and normally held out of contact with the paying-out gear by a spring 44. A weight is connected to one end of the lever 42 by a flexible cable 45. This weight may form the closure 24 for the opening in the bottom of the hull. When the weight is in the opening, the cable 45 is slack, but when the weight is ejected from

the opening, the slack in the cable 45 is taken up and the weight transferred to the lever 42 turns the lever against spring 44 to carry its end into engagement with the teeth on the paying-out gear. This locks the paying-out gear and causes the mine casing 37 to be carried down with the anchor casing 38 and the boat 7 until the weight 24 engages the bottom, whereupon the lever 42 is again turned on its pivot by spring 44 to release the paying-out gear. By reason of this locking of the paying-out gear, the mine casing 37 is carried down with the anchor and when the paying-out gear is released by the weight engaging the bottom, the buoyant mine casing 37 begins to ascend. Its ascent is controlled by a hydrostatic device operating in conjunction with a second lock for the paying-out gear. This hydrostatic device is shown in Fig. 6. It comprises a weight 46 mounted on the cable 40 and adapted to slide thereon. At a point near its end the cable 40 has a sleeve 47 secured to it. In the weight is a transverse opening adapted to receive a rod 48 whose end engages a recess in the sleeve 47 to secure the weight to the cable. The rod 48 is pivotally mounted at its outer end upon a lever 49 pivoted upon the weight 46 and the lever 49 is normally held in the position for locking the weight to the cable by means of the rod 48 by a spring latch 50 extending through an opening in an arm on the weight 46 and into a recess in the end of the lever 49. The latch 50 is connected to the anchor casing 38 by a flexible connection 51, such that when the mine has ascended enough to take up the slack in the connection 51, the latch 50 is withdrawn from its engagement with the lever 49. The purpose of the latch is merely to prevent disengagement of the weight 46 from the cable 40 during the initial downward movement of the boat and the mine carried thereby. After the mine has sunk a substantial distance, the lever 49 and rod 48 are held in the positions in which they are shown in Fig. 6 by a hydrostatic device consisting of a valve 52 connected to the lever 49 and bearing upon a seat formed on the weight 46. A spring 53 in the recess under this seat presses the valve 52 outwardly. While the mine is submerged to a considerable depth, the pressure of the water on the valve 52 holds the latter upon its seat against the tension of spring 53. When the paying-out gear is released by the lever 42 and the mine ascends, the latch 50 is withdrawn during the early part of the ascent and the rod 48 is held in the locking position solely by the hydrostatic device 52. When the mine in its upward movement reaches the depth of submergence at which it is desired that the mine be permanently anchored, the pressure of the spring 53 overcomes the pressure of the water on the outer

side of the valve 52 and the spring presses the valve and the lever 49 outwardly, carrying the end of rod 48 out of the recess in the sleeve 47. The weight 46 being released thus, slides off of the sleeve 47 and down the cable 40 all the way to the anchor casing. At the anchor casing the weight engages a lever 54 pivotally mounted upon the anchor casing at 55 and normally held in the position in which it is shown in Fig. 4 by a shearing pin 56 of soft metal. The blow delivered by the weight to the lever 54 shears the pin 56 and turns the lever 54 on its pivot 55 to carry it into engagement with the teeth on the head of the reel 39. This locks the reel against rotation so that the buoyant casing 37 for the explosive is held at the depth at which this lock for the paying-out gear operated.

Fig. 1 illustrates the boat with the mine therein proceeding on its run upon the surface of the water, the opening in the hull of the boat being closed by the weight 24. This figure also illustrates the second position of the boat after the cover for the opening in the deck has been raised to the upright position and the weight has been ejected from the opening in the bottom. By reason of the ejection of the weight from the opening, water has entered the hull of the boat to such extent as to cause it to sink and also the flexible connection from the weight to the lever 42 has been drawn taut and has operated the lever 42 to lock the paying-out gear of the mine. The figure also shows the boat in a third position resting upon the bottom of the sea. The weight 24 has struck the sea bottom and when the lever 42 was thus relieved of the weight, it was operated by its spring to release the paying-out gear. On such release of the paying-out gear, the buoyant casing 37 for the explosive was permitted to rise until it reached the predetermined depth of submergence as is indicated, at which time the hydrostatically controlled lock for the weight 46 operated to release the weight and allow it to descend to operate the second lock for the paying-out gear.

In combination with the parts above described, an automatic firing mechanism is preferably provided for exploding the mine in case the automatic mechanism for causing the sinking of the boat fails to operate. For this purpose the mine casing 37 has a firing head 58 thereon and a firing pin 59 is mounted opposite this head in suitable guides. A spring 60 is arranged to operate the firing pin 59 when the latter is released by a latch 61 whose end is received in a recess in the pin 59. The detent 61 is operated by a spring 62 acting on a bell-crank lever 63 connected to the detent. One arm of the bell-crank 63 carries the armature of a solenoid 64 which is connected

in the circuit of the electric motor 15. Thus, while the motor is supplied with current from the battery 18, the solenoid 64 is energized and holds its armature attracted against the tension of spring 62, thus maintaining the detent 61 in the notch in the firing pin 59. If the automatic mechanism for ejecting the closure 24 at the end of the selected run were to fail to operate, and instead the boat were to continue on its way propelled by the motor-driven mechanism, the circuit of the motor would be automatically opened, resulting in deenergization of the solenoid 64, withdrawal of the detent 61 by the spring 62 and operation of the firing pin 59 by spring 60 to fire the mine 37. For this purpose a switch 65 is mounted in position to be operated by the arm 26 on continuation of the movement of that arm beyond the position for ejecting the weight 24 and opening the closure 9. The purpose of this mechanism just described is to cause the destruction of the apparatus by explosion of the mine 37 in case of failure of the mechanism to operate in the intended manner so as to guard against the possibility of the apparatus being used by the enemy.

I claim:

1. The combination of a mine-carrying boat; propelling apparatus therefor; means for automatically terminating the operation of said propelling apparatus when the boat has traveled a definite, predetermined distance; and means operated automatically upon the stoppage of the propelling apparatus for laying the mine carried by the boat; substantially as described.

2. The combination of a mine-carrying boat; propelling apparatus therefor; means for automatically terminating the operation of said propelling apparatus when the boat has traveled a definite, predetermined distance; and means operated automatically by said propelling mechanism, when such distance has been traveled, for laying the mine carried by the boat; substantially as described.

3. The combination of a self-propelled boat, a mine carried thereby, automatically-operated mechanism for causing the boat to sink to the bottom immediately the boat has been propelled a selected distance, and automatic means for laying the mine when the boat sinks; substantially as described.

4. The combination of a boat for carrying a mine, an automatic propelling mechanism within the boat, a mine carried by the boat, means operated by the propelling mechanism for opening the hull of the boat immediately upon the conclusion of the run of the boat to permit the entrance of sea water and thus sink the boat, and mine-laying apparatus operated when the boat sinks; substantially as described.

5. The combination of a self-propelled

- boat, a mine carried thereby provided with apparatus for setting and anchoring it in a predetermined submerged position, and means for releasing the mine from the boat 5 to permit it to assume the position of submergence for which it is set immediately the boat has accomplished a run of definite, predetermined length; substantially as described.
- 10 6. The combination of a self-propelled boat, a mine carried thereby, means for automatically laying the mine after it has been carried a predetermined distance by the boat, and means for firing the mine automatically in case of failure of the mechanism 15 to operate; substantially as described.
7. The combination of a boat, a propelling mechanism therefor, a mine carried by the boat, and automatically-operated means for 20 causing the mine to be discharged from the boat as soon as the boat has been propelled a predetermined distance; substantially as described.
8. The combination of a boat, a propelling mechanism therefor, a mine carried by the boat including a buoyant casing for an explosive and means for anchoring the casing at a selected distance below the surface of the sea, and means for automatically effecting 25 the release of the mine as soon as the boat has proceeded a predetermined distance; substantially as described.
9. The combination of a boat, a propelling mechanism therefor, a mine carried by the boat including a buoyant casing for an explosive and means for anchoring the casing at a selected distance below the surface of the sea, and means operated by the propelling mechanism of the boat for effecting the 30 release of the mine as soon as the boat has proceeded a predetermined distance; substantially as described.
10. The combination of a boat, a propelling mechanism therefor, a mine carried by the boat including a buoyant casing for an explosive and means for anchoring the casing at a selected distance below the surface of the sea, means for causing the boat to sink after it has proceeded a predetermined 35 distance, and means whereby the buoyant mine casing is then enabled to rise to the position for which it has been set; substantially as described.
11. The combination of a boat, a propelling mechanism therein, positively-operating mechanism for causing the boat to sink as soon as it has been propelled a predetermined distance, and a buoyant mine carried by the boat which is floated from the boat 40 when the latter sinks; substantially as described.
12. The combination of a boat, a propelling mechanism therefor, a gyroscopic steering mechanism for the boat, means operated by the propelling mechanism for ad-
- mitting water to the hull of the boat to sink it, a buoyant mine casing carried by the boat, means for normally holding the mine casing to the boat, means for releasing said mine casing when the boat sinks to enable 70 it to rise, and an anchor for the mine casing also carried by the boat; substantially as described.
13. The combination, with a mine-carrying boat; of propelling mechanism therefor; mine-laying mechanism; and a device for automatically bringing said mine-laying mechanism into action as soon as the boat has been propelled a predetermined distance. 75
14. The combination, with a mine-carrying boat; of propelling mechanism therefor; mine-laying mechanism; and a device operated automatically by said propelling mechanism, as soon as the boat has traveled a predetermined distance, for bringing said 80 mine-laying mechanism into action.
15. The combination, with a mine-carrying boat; of propelling mechanism therefor; mine-laying mechanism; and a device operated automatically by said propelling mechanism, when the boat has traveled a predetermined distance, for bringing said 85 mine-laying mechanism into action; said device including a member which is settable initially to regulate such distance. 95
16. The combination, with a mine-carrying boat; of propelling mechanism therefor; mine-laying mechanism; a device for automatically bringing said mine-laying mechanism into action when the boat has been 100 propelled a predetermined distance; and means for automatically exploding the mine in case the mine-laying mechanism fails to act at such time. 105
17. The combination, with a mine-carrying boat; of propelling mechanism therefor; mine-laying mechanism; a device for automatically bringing said mine-laying mechanism into action when the boat has been 110 propelled a predetermined distance; and means operated automatically by said device for exploding the mine in case the mine-laying mechanism fails to act at such time. 110
18. The combination, with a mine-carrying boat; of propelling mechanism therefor; mine-laying mechanism; a device operated automatically by said propelling mechanism, when the boat has traveled a predetermined distance, for bringing said 115 mine-laying mechanism into action; and means for automatically exploding the mine in case the mine-laying mechanism fails to act at such time. 120
19. The combination, with a mine-carrying boat; of propelling mechanism therefor; mine-laying mechanism; a device operated automatically by said propelling mechanism, when the boat has traveled a predetermined distance, for bringing said mine-laying mechanism into action; and means operated 125
- 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

automatically by said device for exploding the mine in case the mine-laying mechanism fails to act at such time.

20. The combination, with a mine-carrying boat; of propelling mechanism therefor; mine-laying mechanism; and a device for automatically bringing said mine-laying mechanism into action and terminating the operation of said propelling mechanism 10 when the boat has been propelled a predetermined distance.

21. The combination, with a mine-carrying boat; of propelling mechanism therefor; and a device operated automatically by the 15 propelling mechanism, when the boat has traveled a predetermined distance, for bringing the mine-laying mechanism into action and terminating the operation of said propelling mechanism.

20 22. The combination, with a mine-carrying boat; of propelling mechanism therefor; a controller for terminating the operation of the propelling mechanism; mine-laying mechanism; a controller to release 25 said mine-laying mechanism; and a device

for automatically effecting the operation of both controllers when the boat has been propelled a predetermined distance.

23. The combination, with a mine-carrying boat; of propelling mechanism therefor; a controller for terminating the operation of the propelling mechanism; mine-laying mechanism; a controller to release said mine-laying mechanism; and a device for automatically effecting the operation of both controllers when the boat has been propelled a predetermined distance; said device including an element which is initially settable to regulate such distance.

24. The combination, with a mine-carrying boat; of propelling mechanism therefor; mine-laying mechanism operable automatically to lay the mine when the boat has been propelled a predetermined distance; and means operable automatically to terminate 45 the operation of the propelling mechanism and to explode the mine in case the mine-laying mechanism fails to act.

In testimony whereof I affix my signature.
GIOVANNI EMANUELE ELIA.
